TOOL FOR MAGNETIZING AND DE-MAGNETIZING

Cloyd D. Smith, P.O. Box 338, Reno, Nev. 89101

Filed Aug. 29, 1966, Ser. No. 3,614

Term of patent 14 years

(Cl. D26—1)

FIG. 1

FIG. 2

FIG. 3

FIG. 4

FIG. 5

FIGURE 1 is a perspective view of a tool for magnetizing and de-magnetizing, showing my new design;

FIGURE 2 is an elevational view of one end, the other end being substantially similar in appearance;

FIGURE 3 is an elevational view of one side, the other side being substantially similar in appearance;

FIGURE 4 is a transverse sectional view, the plane of the section being indicated by the line 4—4 in FIGURE 3; and

FIGURE 5 is a longitudinal sectional view, the plane of the section being indicated by the line 5—5 in FIGURE 2.

I claim:

The ornamental design for a tool for magnetizing and de-magnetizing, as shown and described.
